UNITED STATES PATENT OFFICE.

ORRA I. FOSTER, OF HAVERHILL, MASSACHUSETTS.

HAT-HOOK.

SPECIFICATION forming part of Letters Patent No. 357,192, dated February 8, 1887.

Application filed May 6, 1886. Serial No. 201,316. (No model.)

To all whom it may concern:

Be it known that I, ORRA I. FOSTER, of Haverhill, county of Essex, and State of Massachusetts, have invented an Improvement in 5 Hat-Hooks, of which the following description, in connection with the accompanying drawing, is a specification, like letters on the drawing representing like parts.

This invention has for its object to construct 10 a hat-hook which may be readily applied to an ordinary wardrobe-hook or other garment-support.

In accordance with this invention, a strip 15 of material, preferably wire, is bent at one end to form a support for a hat, and at its opposite end to embrace an ordinary hook or projecting support, the said strip being also preferably bent adjacent to the supporting-hook in order that the upright or shank of the 20 hat-hook may lie a sufficient distance from the supporting-hook to which it is attached to permit a coat or other garment to be hung upon the said supporting-hook.

The drawing shows in side elevation a de- 25 tachable hat-hook embodying this invention.

The supporting-hook, having the two sup- 30 porting ends *a b*, is of usual construction.

The hat-hook consists of a strip of metal 35 preferably wire, bent at one end into a circu- lar form, as at *c*, and turned at right angles to the shank or upright *d*, to form a flat support upon which a hat may be placed. The opposite end of the strip of wire is bent over upon itself for a short distance to 40 form a loop or clamp, having the side portions, *e e'*, the extreme end *e'* of the portion *e* being turned over to form an engaging end. The two portions *e e'* are bent or curved inwardly toward each other at a point intermediate of 45 their length, thus forming substantially two loops or eyes to clasp or embrace the hooked ends *a b* of the supporting-hook. The shank *d*, upturned from the portion *e'*, is slightly bent outward at its lower end, or V-shaped, so as to leave a sufficient space at the end of the sup- 50 porting-hook to receive a coat or other garment and not interfere with the shank, and the top portion of the shank *d* is bent at *d'* in

order that the support may be retained in upright position; and it is obvious that the shank 50 *d* may be bent at such point in various directions, according to the shape of the hook to which it is applied.

The engaging end *e'* prevents the device from becoming easily detached from the sup- 55 porting-hook, while the enlarged ends of the supporting-hook also prevents the device from readily detaching itself.

It will be seen that the device herein de- 60 scribed may be readily attached to a hook of ordinary construction, greatly adding to the efficiency of the latter with but trifling cost.

It is obvious that, instead of attaching the device to a supporting-hook upon which other garments may be hung, it may be attached to 65 any other projecting support, and it may also be variously bent to answer the requirements for which it is needed.

I claim—

1. A detachable hat-hook, it consisting of a 70 strip of metal provided with a loop or clamp at one end to embrace the fixed hook or support, and a vertically-extended shank portion upon which the hat is placed, substantially as described.

2. The hat-hook herein described, it con- 75 sisting of a strip of metal provided with a loop or clamp at one end and adapted to receive a hat upon its other end, combined with a hook or support embraced by the said loop or clamp of the hat-hook, substantially as de- scribed.

3. The hat-hook herein described, it con- 85 sisting of a strip of metal bent to form a loop or clamp, and turned upward to form a shank to support the hat, combined with a hook or support to which the said hat-hook is remov- ably attached, substantially as described.

In testimony whereof I have signed my name to this specification in the presence of two 90 subscribing witnesses.

ORRA I. FOSTER.
